UNITED STATES PATENT OFFICE.

EDWARD J. VON PEIN, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND.

CASH REGISTER.

Application filed March 11, 1924. Serial No. 698,436.

This invention relates to cash registers and more particularly to cash registers of the type described in the patent to Kettering and Chryst, No. 1,137,061, issued April 27, 5 1915, to which reference may be had for a complete description of such parts of the machines as do not relate directly to the present invention.

An object of this invention is to provide 10 means to prevent movement of the cash drawer to accessible position so long as its operating mechanism remains in home position.

A further object is to provide means to 15 prevent opening the cash drawer prior to the time the full stroke mechanism becomes effective.

It is an object to positively preclude the 20 opening and subsequent closing of the cash drawer without operation of the various registering and recording mechanisms, etc., with which the register may be equipped.

With these and incidental objects in view, the invention consists of certain novel features of construction and combinations of parts, the essential elements of which are set 25 forth in appended claims and a preferred form of embodiment of which is hereinafter described with reference to the drawings 30 which accompany and form part of this specification.

Of said drawings:

Fig. 1 is a right side elevation with the 35 cash drawer shown in section, several parts of the mechanism being omitted for clearness.

Fig. 2 is a transverse vertical section of the machine, with parts of the mechanism omitted for clearness.

The machine illustrated in the above 40 mentioned patent is of the drawer-operated type, that is, the energy for driving the mechanism during the opening movement of the cash drawer is stored up by the closing 45 movement of the said drawer. The drawer is normally spring-pressed outward, but is restrained from such movement by a latch which is freed to release the drawer upon the depression of certain keys in the machine.

The drawer then opens under spring action 50 and is returned by hand to its closed position. Upon the return movement of the drawer, the amount, clerk's initial, transac-

tion character, etc., set up on the keyboard are recorded on a record strip. 55

Referring to the drawings, only so much of the mechanism is shown as is necessary to clearly illustrate the improvement, the complete mechanism being shown in the Kettering and Chryst patent previously referred to. 60

The machine is operated in the usual manner by depressing the proper keys representing the transaction, after which a release bar 30 (Fig. 1) is operated to release the cash drawer 31 and cause the operation of the machine. The release bar 30 is secured to a forked plate 32, suspended by links 33 and 34 supported on the frame member 35. 65

This release bar is retained in normal position by a spring 36. A pin 37 mounted in a bell crank lever 38 pivoted at 39 is held in engagement with the plate 32 by a spring 40 stretched between the pin and a pin in the plate 32. This causes the bell crank 70

lever 38 to move when the release bar is operated. The lower end of the bell crank lever 38 is formed with two notches 41 and 42, which are engaged by a roller 43 on a rod carried by arms 44 and 50 pinned on a rod 45 (Figs. 1 and 2). A link 51 connects the arm 50 to a drawer latch 52 pivoted at 53 to the frame of the machine. The lower end of the latch 52 is bifurcated to receive a roller 54 carried in the bracket 85

mounted on the rear end of the cash drawer. The roller 43 engages the notch 41, as shown in Fig. 1, to hold the latch in the position shown in Fig. 2, thereby preventing opening 90

movement of the drawer. When the release bar is pushed, the roller 43 is freed from the notch 41, thereby permitting the latch 52 to swing and the drawer to open. The latch is held in its moved position by a spring 95 stretched between the link 51 and a member rigid with the left side frame.

When the latch 52 is freed to move clockwise, a pair of drawer-operating arms 55, mounted on studs 56 on opposite sides of the machine, one arm being shown in Fig. 1, are swung clockwise to move the cash drawer forward. These arms are actuated by a spring 57 (Fig. 2) attached to the frame of the machine and to an arm 58 pivoted on a rod 59 supported in the side frame. The 100 arm 58 is connected by a link 65 to a bell

- crank lever 66 which is pinned to a rod 67. As only the right hand arm of the pair of arms 55 and its associate parts are shown, the description will refer to such parts.
- 6 Pinned to the rod 67 is an arm 68 which is connected by a link 69 and stud 70 to the drawer-operating arm 55 (Fig. 1), by which connecting means the spring 57 operates the drawer-operating arms clockwise. The lower end of the drawer-operating arm carries a roller 71 which engages a block 72 secured to the cash drawer 31. Also fast on the lower end of the drawer-operating arm is a spring-actuated full-stroke pawl 73 which cooperates with notches in a rack plate 74 to compel the drawer-operating arms to be moved forward the proper distance before the cash drawer can be returned to its normal position.
- 10 The drawer-operating arms 55 constitute means for driving the machine, as well as means for storing up energy in the spring 57 as they are moved counter-clockwise by the closing movement of the cash drawer, as is fully explained in the patent previously referred to.
- 15 A link 75 connects the lower end of the bell crank lever 66 with a member 76 pivoted on a stud 77. This member is connected by a pin 78 to a printer writing table 79, also pivoted on the stud 77. The complete printing mechanism is not shown here, as it is fully illustrated and described in the patent to Chryst No. 1,140,443 issued May 25, 1915. Only so much of this mechanism is shown as is deemed necessary properly to set forth the invention.
- 20 The totalizer 85 is supported by a pair of arms 86 pinned to a rod 87, and is normally in engagement with an actuator 88 mounted on a segment 89 pivoted on a stud supported by a key frame and in axial alinement with a stud 90 supported in the side frame of the machine. The segment is actuated in one direction by a spring by which it is held against a rod 91 supported by a pair of arms 92 actuated by a pair of plates 94 pinned to the rod 67, only one arm 92 and plate 94 being shown. The plates 94 are provided with cam slots 93 cooperating with rollers on the arms 92. As the arms 92 are moved counter-clockwise, the segment 89 will assume positions corresponding to an item key depressed, representing the transaction to be recorded, after which the segment 89 will be returned to its normal position by the rod 91, all of which is clearly illustrated and described in the Kettering and Chryst patent previously referred to.
- 25 The engaging and disengaging of the totalizer 85 (Fig. 2) with the actuators 88 is controlled by two plates 95 and 96 (Fig. 1) which are fastened together by pins and secured to the rod 87. A pin 97, carried on the left arm of the bifurcated link 98, nor-
- mally engages a notch 99 formed in the plate 95, and as the machine begins its operation the rod 87 will be rocked and the totalizer 85 will be disengaged from its actuator 88. The lower end of the link 98 is pivoted on a bell crank lever 100, which is pivoted on a screw stud 101. The upper end of the bell crank lever 100 is connected by a link 102 to the upper end of a second bell crank lever 103 pivoted on a pin 104. Mounted on the lower end of the bell crank lever 103 is a roller 110, which engages a cam plate 111 pivoted on a stud 112 supported by the drawer operating arm 55 and held in normal position by a spring 113. As the drawer operating arm 55 swings forward about its pivot 56 the cam plate 111 will cause the bell crank lever 103 and its connecting parts to rock the rod 87 to disengage the totalizer from its actuators. As the drawer operating arm approaches its forward position, the cam plate 111 will engage a roller 114 carried on the bell crank lever 100 and rock this lever clockwise, and cause the totalizer to again engage its actuators 88, in which position it will remain until the next operation. Upon the return of the drawer operating arm 55 to its normal position, the cam plate 111, as it engages the roller 110, will be moved in a clockwise direction against the tension of its spring until the arm 55 reaches a point where the cam plate 111 will clear the roller 110, when the spring 113 will return the plate to its normal position so that the cam plate 111 will not move the bell crank lever 103 counter-clockwise, as the arm 55 returns to its home position.
- 30 For the purpose of maintaining the totalizer in engagement with the actuators on the return movement of the arms 55 and at the time the cam plate 111 engages the roller 110, a lever 115, pivoted at 116 to the rack plate 74 and lying in the plane of the bell crank lever 103, has an upwardly extending projection engaging a downwardly extending projection on the bell crank lever. The lever 115 is held rigid at this time by a pin 117 mounted in the full-stroke pawl 73 engaging the lower edge of the lever. A spring 118 holds the lever 115 in its normal position with a laterally projecting lug 119, engaging the top side of an opening 120 formed in an arm 121 pivoted on a stud 122 supported in the rack plate 74. As the lever is moved clockwise by the forward movement of the drawer operating arm 55 on the right side of the machine, the arm 121 will be raised to place the right hand end 123 out of the path of a bracket 124, which is secured to the cash drawer 31. The function of the arm 121 and the bracket 124 is to intercept the cash drawer after it is released, if pressure is brought to bear on the writing table 79 (Fig. 2) to hold back the drawer operating

arms 55, before the full stroke pawl 73, mounted on the arms 55, engages the first notch in the lower edge of the rack plate 74. After the pawl 73 engages the first notch, it is necessary to complete the operation of the mechanism and make the proper records of the transaction before the drawer can be returned to its inaccessible position. Without this device, it would be possible to have 10 access to the cash drawer without the proper operation of the machine.

This was accomplished by holding the writing table against movement. Through the connecting mechanism this would prevent 15 the drawer operating arms from moving far enough for the full stroke device to become effective, and therefore as the drawer had been released it could move forward, money could be removed therefrom, and it 20 could be closed again without making any record whatever on the detail strip or the totalizer. As above noted, with the present invention in use, if the writing table is held after the release of the machine, the bracket 25 124 will strike the rear end 123 of arm 121 and will prevent the opening of the drawer.

The operation of the device during the proper operation of the machine is as follows: As the motor bar is operated to release 30 the cash drawer and the drawer-operating arms swing forward, the cam plate 111 engaging the roller 110 will move the bell crank lever 108 counter-clockwise and the lever 115 clockwise which will elevate the 35 end 123 of the arm 121 out of the path of the bracket 124 mounted on the cash drawer. As the cash drawer is returned to its home position the bracket 124 will engage the angle edge of the end 123 of arm 121 and slightly 40 raise the arm as the bracket passes under the same.

While the form of mechanism herein shown and described is admirably adapted to fulfill the objects primarily stated, it is to 45 be understood that it is not intended to confine the invention to the one form of embodiment herein disclosed, for it is susceptible of embodiment in various forms all coming within the scope of the claims which follow.

50 What is claimed is:

1. In a machine of the class described, the combination of a cash drawer, a latch adapted to retain said drawer in inaccessible position, manipulative means for operating 55 said latch to release said drawer, driving arms adapted to move said drawer into accessible position, a full-stroke device for said driving arms, a bracket on said cash drawer, an arm adapted to be engaged by said 60 bracket to intercept said drawer, and means operated by said driving arms for raising said intercepting arm out of engaging position with said bracket after said full-stroke device becomes effective.

65 2. In a machine of the class described,

the combination of a cash drawer, a latch adapted to retain said drawer in inaccessible position, manipulative means for operating said latch to release said drawer, driving arms adapted to move said drawer into accessible position, a full-stroke device for said driving arms, means adapted to intercept said drawer, and means operated by said driving arms for moving said intercepting means out of engaging position with said drawer after said full-stroke device becomes effective.

70 3. In a machine of the class described, the combination of a cash drawer, means adapted to retain said drawer in inaccessible position, manipulative means for operating said drawer retaining means, driving means adapted to move said drawer into accessible position, a full stroke device for said driving means, means adapted to intercept said drawer, and means operated by said driving means for moving said intercepting means out of engaging position with said drawer after said full stroke device becomes effective.

75 4. In a machine of the class described, the combination of a cash drawer, a latch adapted to retain said drawer in inaccessible position, manipulative means for operating said latch to release said drawer, driving arms adapted to move said drawer into accessible position, and means adapted to intercept said drawer after it is released if said driving arms are intercepted.

80 5. In a machine of the class described, the combination of a cash drawer, means adapted to retain said drawer in inaccessible position, manipulative means for releasing said drawer retaining means, driving means adapted to move said drawer into accessible position, and means adapted to intercept said drawer after it is released if said driving means is intercepted.

85 6. In a machine of the class described, the combination of an oscillating printer writing table, a driving means adapted to oscillate said writing table, a cash drawer, a latch adapted to retain said drawer in inaccessible position, manipulative means for operating said latch to release said drawer, driving arms adapted to move said drawer into accessible position, and means preventing access to said cash drawer after the operation of said latch if said driving means is restrained by retarding pressure applied 90 to said writing table.

95 7. In a machine of the class described, the combination of an oscillating printer writing table, a cash drawer, a driving means adapted to simultaneously operate said writing table and said cash drawer, and means preventing the operation of said cash drawer when said writing table is restrained.

100 8. In a machine of the class described, the combination of a printer, a totalizer, a 105

cash drawer having accessible and inaccessible positions, latching means for said drawer, and means operative after said drawer is unlatched and before said drawer can be moved to its accessible position to compel operation of said printer and totalizer.

9. In a machine of the class described, the combination of a printer, a totalizer, a

cash drawer having accessible and inaccessible positions, latching means for said drawer, and a subsidiary latching means effective after said first mentioned latch is released and before said drawer can be moved to its accessible position to compel operation of said printer and totalizer.

In testimony whereof I affix my signature.

EDWARD J. VON PEIN.
